UNITED STATES PATENT OFFICE.

ORVILLE M. MORSE, OF JACKSON, MICHIGAN.

GRAIN-SEPARATOR.

SPECIFICATION forming part of Letters Patent No. 499,796, dated June 20, 1893.

Application filed September 27, 1892. Serial No. 447,005. (No model.)

To all whom it may concern:

Be it known that I, ORVILLE M. MORSE, a citizen of the United States, residing at Jackson, in the county of Jackson and State of Michigan, have invented new and useful Improvements in Grain-Separators, of which the following is a specification.

This invention relates to improvements in the separating machine for which Letters Patent No. 441,372, dated November 25, 1890, and Reissue No. 11,165, dated May 12, 1891, were granted to me. The separating machine of said patent contains a separating chamber which has an imperforate peripheral wall, an outlet in one end for the heavy material, an outlet at the opposite end for the light material, and a rotating air propelling device which is located in the separating chamber near the outlet for the heavy material and which causes the air to circulate from the axial portion of the chamber to the peripheral wall near the outlet for the heavy material, thence along the peripheral wall to the outlet for the light material, and thence back through the axial portion of the chamber, so that the circulating air current carries the separated dust to the outlet provided for its discharge from the chamber.

In an application for patent filed September 19, 1892, Serial No. 446,299, I have described and shown improvements in this machine whereby the machine is rendered better adapted for use as a grain scourer and separator, and which consist, generally stated, of contrivances whereby the grain issuing from the separating chamber is separated from the air current which accompanies the grain and whereby the impurities carried on that air current, such as chaff, chess, screenings, &c., are separated therefrom, and the air current is returned to the separating chamber, which latter also performs the function of a scouring chamber.

The improvements which form the subject of my present application, have the object to accelerate the speed or increase the volume of the air current by which the separation is made after the grain has been discharged from the scouring chamber. This object is attained by providing the machine with an

auxiliary fan acting upon the air current and the machine is thereby adapted to make separations for which the air current which is set in motion by the air propelling device in the scouring chamber is insufficient. 55

In the accompanying drawings consisting of four sheets:—Figure 1 is a vertical section of a vertical grain scouring and separating machine provided with my improvements, and having the auxiliary fan arranged below the scouring mechanism, the plane of section being taken in line 1—1, Fig. 2. Fig. 2 is a horizontal section in line 2—2, Fig. 1. Fig. 3 is a vertical section through the fan case in line 3—3, Fig. 2. Fig. 4 is an end elevation of the machine, partly in section, the plane of section being taken in line 4—4, Fig. 1. Fig. 5 is a top plan view of the machine. Fig. 6 is a vertical section through the upper portion of the dust spout and adjacent portion of the scouring chamber, in line 6—6, Fig. 5. Fig. 7 is a sectional elevation of a vertical grain scouring and separating machine provided with my improvements and having the auxiliary fan arranged above the scouring mechanism. Fig. 8 is a vertical section of a scouring chamber containing two sets of scouring devices, one arranged above the other. Fig. 9 is a vertical longitudinal section of a horizontal grain scouring and separating machine provided with my improvements, the plane of section being taken in line 9—9, Fig. 10. Fig. 10 is a transverse section of this machine in line 10—10, Fig. 9.

Like letters of reference refer to like parts in the several figures.

A represents the peripheral wall of the scouring and dust separating chamber which has preferably the form of a frustum of a cone or pyramid. In the upright machine represented in Figs. 1, 2 and 3, this peripheral wall is secured with its lower large end to a bottom plate A' which rests upon the stationary frame of the machine, and with its small upper end to a top plate A². 95

B represents a vertical shaft arranged axially in the scouring chamber and extending below the same. The lower end of the shaft is supported on a bridge-tree b secured to the stationary frame of the machine and the shaft 100

is provided above the bridge-tree with a driving pulley b' . The upper portion of the shaft is supported in a bearing b^2 secured to the top plate A^2 .

5 c represents the feed spout through which the grain or other material operated upon is introduced into the scouring case, and which enters the upper portion of the latter near the center thereof and delivers the grain into a 10 funnel c' secured to the underside of the top plate A^2 . The grain passes from this funnel upon a feed disk C which is secured to the shaft B in the lower portion of the scouring chamber.

15 D represents an annular scouring plate which is arranged horizontally below the feed disk and secured to the shaft by a spider d . This plate carries on its under side the blades E by which the air is set in motion within the 20 scouring chamber. The upper surface of the annular plate is preferably ribbed or roughened to increase the scouring action and its marginal portion is preferably turned upwardly to hold the grain longer on the plate.

25 E The blades E are preferably inclined in the direction in which they rotate for the purpose of lifting the grain in the scouring chamber and retarding its escape therefrom.

f represents the dust escape opening which 30 is formed at the upper or small end of the scouring chamber near the peripheral wall thereof, preferably in the top plate A^2 , as represented in Fig. 6. F represents a dust spout which connects with this opening and extends 35 downwardly on the outer side of the scouring chamber. This dust spout is preferably provided near its upper end with an internal adjustable gate f' .

g represents the grain discharge opening 40 formed in the bottom plate A' of the scouring chamber near the peripheral wall thereof. G represents the chamber into which the grain and air pass which issue from this opening and in which the grain is separated from the accompanying air current. The grain 45 drops from the lower edge of the curved bottom plate g' of this chamber upon an inclined board H which forms the bottom of the grain escape passage, while the air current 50 accompanying the grain reverses its direction and passes upwardly and outwardly between the boards g' and H . The air current is prevented from passing downwardly over the inclined board H with the grain by a flap- 55 valve h which rests upon the grain.

I represents a chaff hopper which is arranged underneath the upper portion of the inclined board H and through which the air current passes after it has separated from the grain. 60 The air current expands in this hopper and drops the heavier grade of impurities such as chaff, &c.

i is a downwardly inclined passage which is arranged underneath the inclined board H 65 and through which the air current escapes from the hopper I .

J is an ascending air passage or leg which is arranged at the lower ends of the inclined board H and air passage i . The grain is delivered from the lower portion of the inclined 70 board H into the ascending air passage above the point at which the air current enters the ascending passage from the inclined passage i , so that the grain drops at this point through the ascending air current whereby 75 any light impurities which are still commingled with the grain are removed. The ascending air passage may be provided with an adjustable wall j for regulating the force of the air current.

80 K represents a chess hopper which is arranged on the outer side of the ascending air passage J and in which the air current parts with the lighter grades of impurities, such as screenings, &c.

k is a horizontal air passage which extends inwardly from the top portion of the chess hopper K and which communicates at its upper side with the central portion of the scouring chamber by an opening k' .

85 L is a fan case which is arranged underneath the horizontal air passage k around the shaft B and which contains blades l which are secured to the shaft B .

l' is the eye of the fan which is formed in 90 the upper head of the fan case and which communicates with the horizontal air passage k so as to draw the air therefrom.

l^2 is the blast spout of the fan through which the air current is delivered into some portion 100 of the air separating contrivance through which the air current passes which escapes with the grain from the scouring chamber. I prefer to connect the exit end of the blast spout with the chaff hopper, I , as shown in 105 Fig. 2 and as indicated in dotted lines in Fig. 1, but it may be connected with the passage leading from the chamber G to the hopper I or with some other part through which the air current passes which escapes with the 110 grain.

The air current set in motion by the fan 115 unites with the air current issuing with the grain from the scouring chamber and flows with the same through the separating contrivances in which the impurities are separated from the air current, or through some of these contrivances, and so facilitates and increases the separating action. After having passed through these separating contrivances the air current is divided, one part passing into the eye of the fan case and the other part into the central opening of the scouring chamber, and as these openings are in communication with each other and the air passage k a perfect equilibrium of the air is maintained in the several parts of the machine.

120 The air passage k may be provided with an adjustable valve k^2 for regulating the air current through the same.

125 The peripheral wall l^3 of the fan case may

be tapered upwardly as shown in Figs. 1 and 3, and may be provided with a dust discharge pipe l^4 at its upper end for the purpose of separating from the air any fine dust which may still be contained in it when it reaches the fan.

In the vertical machine represented in Fig. 7 the fan is arranged above the scouring chamber and the blast spout of the fan is connected with the upper end of the chaff hopper I, while the chess hopper K is connected with the eye of the fan by an ascending air spout k^3 . The grain is delivered by the feed spout c into a feed saucer C'.

If desired, the scouring chamber may be provided with two sets of scouring devices arranged one above the other, as represented in Fig. 8. In the construction represented in this figure the grain escapes from the upper scouring device through one or more openings m formed in a horizontal diaphragm M secured in the scouring chamber and falls upon a funnel m' by which it is conducted from the periphery toward the center of the scouring chamber, where it falls upon a feed saucer C^2 from which it is thrown upon an annular plate D' to which the lower blades E' are secured. The grain, after having been scoured in the lower portion of the scouring case, escapes through the opening g in the bottom plate A'. The lower portion of the scouring case is provided underneath the horizontal diaphragm M with a dust discharge opening f^2 which is connected with the dust spout F by a branch spout F'.

In the horizontal machine represented in Figs. 9 and 10, the shaft B is arranged horizontally and the fan blades are secured to the shaft near the large head A' of the scouring chamber. The fan case communicates at one side with the interior of the scouring chamber by an opening O and at the opposite side with the upper part of the chess hopper K by an opening O'. The blast spout O² of the fan is connected with the upper part of the chaff hopper I. The opening g, through which the grain and air escape from the scouring chamber, discharges into a chamber P which has in its bottom an opening p through which the grain falls upon the inclined board H, while the air current issuing with the grain moves outwardly to the top of the chaff hopper I and unites with the air current issuing from the blast spout of the fan and flows with said air current through the separating hoppers and their connecting passages and back to the fan case where the air current is divided, one part flowing into the scouring chamber through the opening O and the other part escaping through the blast spout of the fan.

I do not intend to claim in this application any improvement which is described in my aforesaid pending application, but

65 I claim as my invention—

1. The combination with the scouring and

dust separating chamber having a dust outlet at one end, a grain outlet at the other end and an internal air propelling device, and the air separator through which the air issuing from the grain outlet flows and from which it is returned to the scouring chamber, of an auxiliary fan which is connected with said air separator and whereby the movement of the air through the same is promoted, substantially as set forth.

2. The combination with the scouring and dust separating chamber having a dust outlet at one end, a grain outlet at the other end and an internal air propelling device, of a chamber which is connected with the grain outlet and in which the grain is separated from the accompanying air current, a return passage whereby the air current is conducted back to the scouring chamber and a fan having its blast spout and its eye connected respectively with said passage near its inlet and outlet ends, substantially as set forth.

3. The combination with the scouring and dust separating chamber having a dust outlet at one end, a grain outlet at the other end and an internal air propelling device, of a chamber which is connected with said grain outlet and in which the grain is separated from the air current, a grain passage leading from said chamber, an air passage intersecting said grain passage and through which the air flows from said chamber toward the scouring chamber, and a fan having its blast spout and its eye connected with said passage respectively in advance and in rear of its intersection with the grain passage, substantially as set forth.

4. The combination with the scouring and dust separating chamber having a dust outlet at one end, a grain outlet at the other end and an internal air propelling device, of a chamber which is connected with said grain outlet and in which the grain is separated from the air current, a chaff hopper into which the air current flows from said chamber, an air passage leading from said chaff hopper and intersecting the grain passage, a fan having its blast spout connected with said chaff hopper and a return spout leading to the fan and the scouring chamber, substantially as set forth.

5. The combination with the scouring and dust separating chamber having a dust outlet at one end and a grain outlet at the other end and an internal air propelling device, of a chamber which is connected with said grain outlet and in which the grain is separated from the air current, a chaff hopper into which the air current flows from said chamber, an air passage leading from said chaff hopper and intersecting the grain passage, a chess hopper receiving the air current from said passage, a return air passage connecting the chess hopper with the scouring chamber, and a fan having its blast spout con-

nected with the chaff hopper and its eye with the return air passage, substantially as set forth.

6. The combination with the scouring and dust separating mechanism and an air separator receiving the grain and air discharged therefrom, of a fan connected with said air separator to promote the movement of the air through the same and having a taper-

ing fan case provided with a dust discharge spout at its small end, substantially as set forth.

Witness my hand this 16th day of September, 1892.

ORVILLE M. MORSE.
